UNITED STATES PATENT OFFICE.

FREDRICK W. SMITH, OF MINNEAPOLIS, MINNESOTA.

TOBACCO PIPE.

1,427,762.

Specification of Letters Patent. Patented Aug. 29, 1922.

Application filed October 16, 1919. Serial No. 330,974.

To all whom it may concern:

Be it known that I, FREDRICK W. SMITH, a citizen of the United States, residing at Minneapolis, in the county of Hennepin and State of Minnesota, have invented certain new and useful Improvements in Tobacco Pipes; and I do hereby declare the following to be a full, clear, and exact description of the invention, such as will enable others skilled in the art to which it appertains to make and use the same.

My invention relates to tobacco pipes and has for its object to improve both the smoking action and the cleaning facility thereof. Generally stated, the invention consists of the novel devices and combinations of devices hereinafter described and defined in the claims.

The improved pipe, in its preferred form, is illustrated in the accompanying drawings wherein like characters indicate like parts throughout the several views.

Referring to the drawings:

Fig. 1 is a vertical section taken axially 25 through the pipe;

Fig. 2 is a section on the same line as Fig. 1, showing the stem removed from the bowl member;

Fig. 3 is an enlarged section on the line 30 3—3 of Fig. 1; and

Fig. 4 is a section on the same line as Fig. 3, but illustrating a different adjustment of the parts.

The tobacco bowl 5 is provided with a 35 tubular shank 6 that forms a part of the complete stem of the pipe. The shank 6 is formed with a cylindrical axial passage 7 which, at its inner end, is connected to the bottom of the interior of the bowl by a small port 8. A long longitudinal channel-like port 9 is formed in the passage 7 but extends less than from end to end of the latter. Preferably, this long port 9 is at the top of the shank. The numeral 10 indicates a 45 metal ferrule applied to the end of the shank 6.

The stem proper, which is sometimes designated as the "bit" indicated by the numeral 11, is provided with an axially projecting stem extension 12 in the form of a metallic tube, one end of which is set into the stem 11 so that it is rigidly secured thereto. This stem extension 12 snugly fits the cylindrical passage 7 of the shank 6 and 55 is adapted to both slide and rotate therein under sufficient friction to prevent accidental

rotations of the stem in respect to the shank. At a point a considerable distance outward from its extreme inner end, the stem extension 12 is provided with a plug 13, and between its end and this plug, it is provided with one or more, as shown, three radial ports 14. The end of the stem extension 12 is filled with a porous filtering material 15 preferably afforded by a small piece of sponge. In longitudinal alignment with the ports 14, the stem extension 12 is provided with a port 16 located between the plug 13 and the stem 11, being quite close to the extreme inner portion of the latter. Stem 11 is further provided with a small tubular extension 17 that is spaced concentrically within the cylindrical extension 12 and terminates short of the plug 13. The shank 6, at a point preferably ninety degrees from the radial plane of the long port 9, is provided with a so-called blow-off port 18, which, as shown, extends through the ferrule 10.

When the pipe is to be used, the stem or 80 bit 11 is turned into the position shown in Figs. 1 and 3 and the line of travel will then be from the bowl 5 through port 8, thence through filtering material 15 and ports 14 into channel 9, thence through port 85 16 into the interior of the stem extension 12, thence through tube 17, through stem 11. Moisture and the nicotine will be caught and held by the filtering material 15 so that only clean smoke, free from nicotine, will 90 be delivered to the mouth of the smoker. When the sponge or filtering material 15 becomes saturated, it may be replaced or may be quickly and easily cleaned, simply by removing and squeezing the same and replacing the same in position.

The interior of the tubular stem extension 12, outward of the plug 13 affords a saliva chamber or trap for the collection of saliva, so that the pipe bowl will be kept 100 dry. If at any time there is a considerable accumulation of the saliva in the saliva trap, it is only necessary to turn the stem so that the ports 14 will be closed and the port 16 will be turned into registration with the 105 blowoff port 18. When this is done and air is blown through the stem 11, the only escape for the saliva will be outward through the aligned ports 16 and 18, and hence, the saliva trap or chamber can be cleaned out 110 quickly at any time. Fig. 4 shows the stem turned into the blowoff position just de-

scribed, while Figs. 1 and 3 show the stem in position for smoking. As the channel 12 is at the top, very little, if any, accumulation will be held in the said port. This pipe, 5 therefore, is sanitary, will not quickly become clogged, and may be very quickly and easily cleaned.

What I claim is:

1. In a tobacco pipe, the combination with 10 a bowl having a tubular shank, of a stem having a sleeve-like extension telescoped within said shank and rotatable therein, said stem extension having a plug therein and peripheral ports normally disposed at the 15 top thereof both inward and outward thereof, said shank having an internal channel extending along the top of said extension with which the said ports are adapted to be aligned when the pipe is in condition for 20 smoking said extension closely fitting said shank peripherally, except at said channel.
2. In a tobacco pipe, the combination with 25 a bowl having a tubular shank, of a stem having a sleeve-like extension telescoped within said shank and rotatable therein, said stem extension having a plug and peripheral ports both inward and outward thereof, said shank closely fitting said extension peripherally, except for a small internal channel at the top thereof with which the ports 30 of said extension are adapted to be aligned when the pipe is in condition for smoking, and a filtering material in the inner end of said stem extension through which the smoke 35 must be passed to the inner ports of said stem extension.
3. In a tobacco pipe, the combination with 40 a bowl having a tubular shank, of a stem having a sleeve-like extension telescoped within said shank and rotatable therein, said stem extension having a plug and peripheral ports both inward and outward thereof, said shank having an internal channel with which the ports of said extension are adapted to

be aligned when the pipe is in condition for 45 smoking, the said shank having a blow-off port out of line with the internal channel thereof, and with which the outer ports of said stem extension are adapted to be aligned by rotation of the stem, for the 50 purposes stated.

4. In a tobacco pipe, the combination with 55 a bowl having a tubular shank, of a stem having a sleeve-like extension telescoped within said shank and rotatable therein, said stem extension having a plug and peripheral ports both inward and outward thereof, said shank having an internal channel with which the ports of said extension are adapted to be aligned when the pipe is 60 in condition for smoking, a filtering material in the inner end of said stem extending through which the smoke must be passed to the inner ports of said stem extension, the shank of said bowl having a blow-off port 65 out of line with the internal channel thereof, and said stem being rotatable to close the inner ports of said stem extension and to align the outer port of said stem extension with said blowoff port.

5. In a tobacco pipe provided with a bowl 70 having a tubular shank, a stem having a sleeve-like extension telescoped within said shank and rotatable therein, said extension closely fitting said shank except for a small 75 channel extending along the top thereof, a plug in said extension and peripheral ports at the top of said extension both inward and outward of said plug communicating with said channel, said stem having the 80 usual longitudinal aperture therethrough, and a tube projecting from the inner end thereof into said extension but terminating short of said plug.

In testimony whereof I affix my signature

FREDRICK W. SMITH.
